[57] CLAIM

The ornamental design for a lighting support assembly, as shown and described.

DESCRIPTION

FIG. 1 is an isometric view of a lighting support assembly;

FIG. 2 is a rear elevational view thereof;

FIG. 3 is a front elevational view thereof;

FIG. 4 is one side elevational view thereof;

FIG. 5 is the opposite side elevational view thereof;

FIG. 6 is a top plan view thereof;

FIG. 7 is a bottom plan view thereof; and

FIG. 8 is an isometric view thereof on an enlarged scale.

FIG. 1

FIG. 2

FIG. 6

FIG. 4

FIG. 3

FIG. 5

FIG. 7

FIG. 8
